CASH REGISTER

Leo G. A. Kömmling, Berlin, Germany, assignor
to The National Cash Register Company, Dayton, Ohio, a corporation of Maryland

Application August 20, 1935, Serial No. 37,067
In Germany August 30, 1934

11 Claims. (Cl. 101—93)

This invention relates to cash registers and the like, but is more particularly directed to the impression mechanisms of such machines.

Generally it is an object of this invention to devise novel means to control the impression mechanisms of cash registers and like machines.

A more specific object is to provide means to vary the number of working strokes of the impression mechanism depending upon the type of record material being used.

Another object is to provide a machine, having a single impression means adapted to perform a varying number of printing strokes to make imprints upon different types of record material, with means to govern the number of printing strokes of said impression means to suit the type of record material being used.

A further object is to supply an impression device, adapted to make two impressions upon one type of record material and one impression upon another type of record material, with controlling means cooperating with one type of record material to govern the printing movements of said impression device.

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification:

In the drawing:

Fig. 1 is a side elevation, as observed from the lefthand side of the machine, showing the impression mechanism and the controlling means therefor.

Fig. 2 is a detail view of the impression hammer and the mechanism that governs the impression strokes thereof.

General description

The machine embodying the present invention has mechanism consisting of a single line of type carriers and a single hammer cooperating therewith, adapted to print either upon an issuing receipt or upon an insertable slip. The issuing receipt has a detachable stub, consequently it is desirable to make two identical impressions upon said receipt, one upon the body thereof and one upon the detachable stub. The double printing upon the issuing receipt is effected by imparting two impression strokes to the hammer each machine operation, said receipt being fed during the interval between impression

strokes of the hammer to present different portions thereof to the impression means.

In slip printing operations, the slip is inserted in a suitable receptacle or slip chute, provided therefor and moved in the path of a slip feeler mechanism to obstruct movement of said feeler which by means of connecting mechanism prevents the second impression stroke of the hammer, thereby allowing only one impression to be made upon the insertable slip.

A manipulative device with two positions, namely "check" and "slip" renders the feeler mechanism inoperative when in "check" position and simultaneously causes a closure to obstruct the slip chute to prevent the insertion of slips therein. Moving the manipulative device to "slip" position opens the closure to the slip chute and enables the slip feeler mechanism.

Detailed description

Referring to Figs. 1 and 2, the machine of this invention has a plurality of type wheels 10 rotatably mounted on a shaft 11 supported by the printer framework not shown, said type wheels being positioned in adding operations by means of depressible amount keys (not shown) and in total taking operations by means of a series of totalizer wheels (not shown) as they are returned to zero. An impression hammer 12, turnably mounted on a shaft 13 supported by the main framework of the machine, carries a platen block 14 which in cooperation with the type wheels 10 and an inking ribbon (not shown) makes imprints either upon an issuing check or receipt or upon an insertable slip.

The hammer 12 is actuated by means of lobes 15 and 16, of a hammer operating cam 17, in cooperation with a roller 18 carried by a lever 19 journaled on a stationary stud 20. The lever 19 carries a stud 21, which is urged by a comparatively weak spring 22, tensioned between said lever 19 and the hammer 12, into contact with a rearwardly disposed surface of said hammer 12. A comparatively strong spring 23, one end of which is connected to the lever 19, urges said lever counterclockwise to maintain the roller 18 in contact with the periphery of the cam 17. The cam 17 is secured on the shaft 13 and moves in unison therewith one clockwise revolution each machine operation.

When the machine is at rest and the cam 17 is in home position, as here shown, a high portion 24 of the periphery thereof is in contact with the roller 18 and retains the hammer retracted as here shown. Due to the contour of the cam 55

17 rotation thereof during machine operation causes the hammer 12 to move slowly counterclockwise under the influence of the lever 19 and the spring 23. Continued rotation of the cam 17 5 causes the lobe 15 in cooperation with the roller 18 to rock the lever 19 clockwise, the hammer 12 moving in unison therewith under influence of the spring 22 in preparation for the first impression blow. When the roller 18 rides off of the 10 abrupt edge of the lobe 15 the spring 23 imparts sharp counterclockwise movement to the lever 19 and the hammer 12. This counterclockwise movement of the lever 19 is suddenly terminated, by means of the roller 18 contacting a low surface 15 of the periphery of the cam 17, just before the platen 14 moves the inking ribbon and the record material into contact with the type wheels, however, momentum of the hammer 12 is sufficient to complete the impression stroke regardless of 20 the spring 22. The lobe 16 effects a second impression blow of the hammer in exactly the same manner as the lobe 15.

Control of the impression hammer in slip printing operations

25 As stated previously, it is desirable that only one imprint be made upon the insertable slip, and this is accomplished by means of a feeler mechanism which prevents the second impression stroke of the hammer when a slip is inserted in 30 the machine, and prevents both strokes of the hammer when no slip is inserted in the machine. The feeler mechanism for controlling the impression strokes of the hammer will now be described 35 in detail.

The insertable slips are presented to and located in relation to the printing mechanism by means of a slip chute 25 (Fig. 1) supported between the frames of the printer mechanism and 40 having an aperture 26, in a case or cabinet 27, which encloses the mechanism of the machine, for the introduction of said insertable slips. The top and bottom plates of the slip chute 25 each has a matched opening 28 arranged to register 45 with the upper end of a slip feeler 29 mounted for vertical sliding movement by means of vertical slots therein in cooperation with two stationary studs 30 secured in the printer framework.

The feeler 29 has a horizontal slot 31 which 50 embraces a stud 32 in a crank 33 secured on a shaft 34 journaled in the printer framework. Also secured on the shaft 34 is a crank 35 which is pivotally connected to one arm of a bell crank 36 fulcrumed on a stationary stud 37. The other 55 arm of the bell crank 36 carries a stud 38 which extends within a slot in one end of a link 39, the other end of which link is pivotally connected to an arm 40 loose on a shaft 41 supported by the main framework and integral with a similar arm 60 42. The arm 42 carries a roller 43 which is urged by a spring 44, the upper end of which is connected to the fulcrum point between the cranks 35 and 36, into communication with the periphery of a cam 45 secured on a shaft 46, said cam 65 and said shaft making one counterclockwise rotation each machine operation. The spring 44 through the crank 35, shaft 34 and crank 33, urges the feeler 29 upwardly.

70 *Printer control lever*

Whether or not the feeler mechanism is effective depends upon the position of a printer control lever 47 (Fig. 1) fulcrumed on a stud 48 secured in one of the machine frames. The lever 75 47 has a suitable fingerpiece which extends

through an aperture in the cabinet 27. The lever 47 has two positions, namely, "check", in which it is here shown, and "slip", indicated by dot and dash lines, and is retained in either of its positions by means of two V-shaped notches therein 5 in cooperation with the rounded nose of a retaining pawl 49 pivoted on a stud 50 and urged into communication with said V-shaped notches by a spring 51.

The printer control lever 47 has therein a camming slot 52 which cooperates with a roller 53 carried by an arm 54 secured to one end of a sleeve 55 rotatably supported by a shaft 56 journaled in the machine framework. Secured on the other end of the sleeve 55 is an arm 57 with 10 a stud 58 embraced by an angular slot 59 in an arm 60 secured on a shaft 61 journaled in the printer framework. Also secured on the shaft 61 is an arm 62 with a bent-over ear 63 which 15 cooperates with a shoulder 64 of the feeler 29. 20

When the lever 47 is in "check" position, as here shown, the train of mechanism described above positions the arm 62 so that the bent-over ear 63 in cooperation with the shoulder 64 prevents upward movement of the feeler 29, under 25 influence of the spring 44, when a lobe 65 of the cam 45 moves out of the path of the roller 43 at the beginning of machine operation. It is therefore evident that when the lever 47 is in "check" position the feeler mechanism is rendered 30 inoperative and the hammer 12 is free to make two impression strokes to make two identical imprints upon the issuing check. Likewise when the printer control lever 47 is in "check" 35 position a closure 66 secured on the shaft 61 is 35 so positioned that a curved portion 67 thereof, which coincides with a slot in the bottom plate of the slip chute 25, closes the opening to said slip chute 25, thus preventing the insertion of slips at this time. It should be here noted that the 40 curved portion 67 of the closure 66 does not extend completely across the slip chute, but only so far as is necessary to prevent the insertion of slips. This enables the machine to issue checks during check printing operations when the curved 45 portion of the closure member is in effective 50 position.

Lever 47, through mechanism which forms no part of the instant invention, controls the operation of the check feeding rollers 80. When 50 this lever is moved into "slip" position, it causes the eccentric mounting 81 for the lower roller 80 to be actuated to move the lower roller from contact with the upper roller and accordingly disables the check feeding rollers in slip printing. 55 Further details of the mechanism for controlling the check feed rollers may be found in the United States application for Letters Patent, Serial No. 734,537, filed July 10, 1934, by Kurt Vogelgesang and Erich Wagner.

Moving the lever 47 clockwise to "slip" position by means of the slot 52 in cooperation with the roller 53 rocks the arm 54, the sleeve 55 and arm 57 counterclockwise. Counterclockwise movement of the arm 57 by means of the stud 58 in cooperation with the slot 59 rocks the arm 60, the shaft 61, and the arm 62 clockwise to disengage the ear 63 from the shoulder 64 to render the slip feeler mechanism effective. Obviously the closure 66 moves clockwise in unison with the shaft 61 to the position indicated by dot and dash lines to remove the curved portion 67 thereof from the opening of the slip chute 25 to permit the insertion of slips therein.

The operation of the impression hammer 12 75

(Fig. 2) is governed by a detent 68, loose on the shaft 34, which is positioned by the slip feeler mechanism. The detent 68 has a concentric slot 69, which cooperates with a stud 70 in an arm 71 secured on the shaft 34. A spring 72 forms a flexible connection between the arm 71 and the detent 68 and urges the detent 68 clockwise to normally maintain the left end of the slot 69 in contact with the stud 70, as here shown.

10 *Slip printing operations*

In slip printing operations, operating the machine with a slip improperly inserted in the chute 25, (Figs. 1 and 2) or with no slip inserted in the chute 25, permits the feeler 29 to move full distance upwardly, under influence of the spring 44, when the lobe 65 of the cam 45 moves beyond the roller 43. This permits full counterclockwise movement of the shaft 34 and the arm 71 and causes said arm 71 to carry the detent 68 counterclockwise in unison therewith, to the position indicated by dotted lines, to move a shoulder 73 thereof in the path of a right-angled extension 74 of one arm of the hammer 12, to obstruct impression movement of said hammer under influence of the cam 17, as explained earlier herein.

An example of a slip printing operation with the slip properly inserted in the chute 25 will now be given. The contour of the cam 17 (Fig. 2) is such that initial movement of said cam in cooperation with the roller 18, the lever 19, and the stud 21, rocks the hammer 12 a sufficient distance counterclockwise to move a roller 75 carried thereby into the path of an extension 76 of the detent 68. This occurs before the lobe 65 of the cam 45 moves beyond the roller 43 and consequently movement counterclockwise of the detent 68, arm 71 and the shaft 34 and the upward feeling movement of the feeler 29, under influence of the spring 44, are obstructed and these parts are retained in their ineffective positions as here shown, while the hammer 12 moves slowly upwardly under influence of the cam 17. When the lobe 15 of the cam 17 retracts the hammer 12, in preparation for the first impression stroke, the roller 75 moves beyond the extension 76 permitting the spring 44 to move the feeler 29 upwardly until such movement is stopped by the slip contacting the top plate of the chute 25. This rotates the shaft 34 a slight distance counterclockwise to move the detent 68 to the position indicated by dot and dash lines.

During the first imprinting stroke of the hammer 12, caused by the lobe 15 of the cam 17 moving beyond the roller 18, the roller 75 engages the extension 76 and moves the detent 68 independently of the arm 71 and the shaft 34 in a counterclockwise direction from the position indicated by dot and dash lines to the position indicated by dotted lines. This independent counterclockwise movement of the detent 68 causes a spring-pushed pawl 77 carried by said detent to drop behind a step 78 of a disk 79 secured on the shaft 34, said step 78 having moved in unison with the shaft 34 from the position shown in Fig. 2 to the position indicated by dot and dash lines. This retains the detent 68 in its effective position against the action of the spring 72 during the second impression stroke of the hammer. The detent 68 does not interfere with the first impression stroke of the hammer because the extension 76 has moved beyond the shoulder 73 before the detent 68 is fully moved to effective position. Retraction of the hammer

by the lobe 16 of the cam 17 in preparation for the second imprinting stroke, causes the extension 74 to by-pass the shoulder 73 and the spring 44 immediately returns said shoulder into the path of the extension 74. Obviously this blocks 5 the second imprinting stroke of the hammer 12 when the lobe 16 of the cam 17 rides off the roller 18 and it is therefore clear that only one imprint will be made upon the insertable slip.

Near the end of machine operation the lobe 65 10 of the cam 45 (Fig. 1) in cooperation with the roller 43 and connecting mechanism imparts clockwise movement to the shaft 34 to return the feeler 29 downwardly to ineffective position, as here shown. The arm 71 and the spring 72 cause 15 the detent 68 to move clockwise in unison with the shaft 34 until an upward extension of the pawl 77 engages a stationary stud 79 to disengage said pawl from the step 78, thus permitting the spring 72 to impart relative movement to said 20 detent 68, to restore it to normal position, as here shown, which position is determined by means of the slot 69 in cooperation with the stud 70. Further explanation of operation is deemed unnecessary as it is believed that a thorough understanding 25 of the functioning of the impression mechanism will have been obtained from a perusal of the foregoing specifications.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which 35 follow.

What is claimed is:

1. In a printing device adapted to print optionally upon a check or slip, the combination of an impression hammer; means to impart two impression strokes to the hammer each machine operation; and means, rendered effective by the hammer during its first impression stroke in a slip printing operation, to prevent the second impression stroke of said hammer. 45

2. In a machine of the character described, having a printing device adapted to make a varying number of imprints, the combination of an impression hammer; means to impart two impression strokes to the hammer each machine operation; a member to block the second impression stroke of the hammer; and means on the hammer, cooperable with the member during the first impression stroke of the hammer, to move the member to effective position to block 55 the second impression stroke of the hammer. 50

3. In a machine of the class described, adapted to make one imprint upon an insertable slip, and a plurality of imprints upon an issuing check, the combination of a receptacle for the slip; a 60 feeler device associated with the receptacle and the slip; an impression hammer; means to impart two impression strokes to the hammer each machine operation; and a member controlled by the feeler device and operated by the hammer 65 during its first impression stroke to prevent the second impression stroke of said hammer.

4. In a machine of the character described, adapted to make a varying number of imprints depending upon the type of record material, issuing check or insertable slip, being used, the combination of a receptacle for the slip; a feeler device associated with the receptacle; manipulative means to render the feeler device operative or inoperative; an impression hammer; means to 70 75

- impart two impression strokes to the hammer each machine operation; means controlled by the feeler device to render the impression means inoperative when a slip is not in the chute, and 5 to prevent second impression movement of the hammer when a slip is inserted in the chute.
5. In a machine of the class described adapted to make a varying number of imprints upon an issuing check and upon an insertable slip, the 10 combination of an impression hammer; means to impart two impression strokes to the hammer each machine operation; a receptacle for the slip; a feeler mechanism associated with the receptacle and the slip; a shaft controlled by the feeler mechanism; a member on the shaft adapted to be moved in unison therewith to prevent operation of the impression means during a slip printing operation when no slip is inserted in the receptacle; and means to move the member relatively 15 to the shaft to prevent the second impression stroke of the hammer when a slip is inserted in the receptacle.
6. In a machine of the class described, adapted to make a different number of imprints upon an 20 issuing check and upon an insertable slip, the combination of a receptacle for the slip; a feeler device associated with the receptacle; means to operate the feeler device; manipulative means to render the feeler device operative or inoperative; 25 an impression hammer; means to impart two impression strokes to the hammer each machine operation; a shaft controlled by the feeler device; a member on the shaft adapted to be moved in unison therewith to prevent operation of the 30 impression means during a slip printing operation when no slip is inserted in the receptacle; and means to move the member relatively to the shaft to prevent the second impression stroke of the hammer when a slip is inserted in the receptacle.
- 40 7. In a machine of the character described, having a printing mechanism including a plurality of type carriers and adapted to make a different number of imprints upon an issuing check and upon an insertable slip respectively, the combination of an impression hammer associated with the type carriers; means to impart two imprinting strokes to the hammer each machine operation; a receptacle for the insertable slip; a feeler associated with the receptacle; a shaft; an element on the shaft, said shaft and said element adapted to be positioned under the control of the feeler; a member on the shaft arranged to cooperate with the hammer to govern the impression strokes thereof; means 45 flexibly connecting the element to the member, whereupon positioning of the shaft and the element under the control of the feeler, when no slip is in the chute, moves the member in unison with said shaft to prevent the hammer from making an impression stroke; and means whereby the 50 hammer moves the member relatively to the element and the shaft to prevent the second impression stroke of said hammer when a slip is inserted in the chute.
- 55 8. In a machine of the class described, having a printing mechanism including a plurality of type carriers and adapted to make a plurality of imprints upon an issuing check and one imprint upon an insertable slip, the combination of an impression hammer adapted to cooperate with the type carriers; means to impart two 60 imprinting strokes to the hammer each machine

operation; a slip chute to guide the slip to the printing mechanism; a feeler device associated with the chute; a shaft controlled by the feeler device and arranged to be located thereby in one position when no slip is in the chute, and arranged to be located by said feeler mechanism in another position when a slip is in the chute; an element arranged to move in unison with the shaft; a member flexibly connected to the element and adapted to control the imprinting 10 strokes of the hammer, whereupon movement of the shaft to one position causes the member to block imprinting movement of the hammer when no slip is in the chute; and means rendered effective, when the shaft occupies its other position, to move the member relatively to said shaft to block the second impression stroke of the hammer when a slip is inserted in the chute.

9. In a machine of the class described having a printing mechanism including a plurality of type wheels, adapted to make imprints upon record material, the combination of an impression hammer cooperating with the type wheels; means to impart two working strokes to the hammer each machine operation; a feeling means; a shaft; an element on the shaft; a member flexibly connected to the element and arranged to control the impression strokes of the hammer; means controlled by said feeling means to impart a certain degree of movement 30 to the shaft, the member and the element, to cause the member to block impression movement of the hammer, said imparting means also adapted to be controlled by said feeling means to impart another degree of movement to the 35 shaft, the member and the element; and means effective after the member has received the latter degree of movement to move said member relatively to the element and the shaft to block the second impression stroke of the hammer. 40

10. In a machine of the character described having a printing mechanism including a plurality of type wheels adapted to make imprints upon record material, the combination of an impression hammer associated with the type wheels; means to impart two working strokes to the hammer each machine operation; a member to control the impression strokes of the hammer; means on the hammer effective during the first working stroke thereof to move the member to effective position to prevent the second impression stroke of the hammer; and means to move the member into cooperative alinement with the moving means on the hammer. 45

11. In a machine of the character described having a printing device including a plurality of type wheels adapted to make imprints upon record material, the combination of an impression hammer associated with the type wheels; means to impart two working strokes to the 60 hammer each machine operation; an element to control the impression strokes of the hammer; a projection on the hammer adapted to cooperate with the element; means including a feeler device to move the element into cooperative alinement with the projection, whereupon the first impression stroke of the hammer moves the element to effective position to prevent the second working stroke thereof; and means to retain the element in effective position until near 70 the end of a machine operation.

LEO G. A. KÖMMLING.
